UNITED STATES PATENT OFFICE.

JOHN D. MORGAN, OF SUMMIT, NEW JERSEY, ASSIGNOR TO STEEL UTILITIES,
INCORPORATED, A CORPORATION OF NEW YORK.

LABEL-DATING MACHINE.

1,280,275.

Specification of Letters Patent.

Patented Oct. 1, 1918.

Application filed September 20, 1917. Serial No. 192,279.

To all whom it may concern:

Be it known that I, JOHN D. MORGAN, a citizen of the United States, and a resident of Summit, in the county of Union and State 5 of New Jersey, have invented certain new and useful Improvements in Label-Dating Machines, of which the following is a specification.

The invention relates to label dating machines, and in certain of its aspects more particularly to label notching machines operated by man power.

Objects and advantages of the invention will be set forth in part hereinafter, and in 15 part will be obvious herefrom, or may be ascertained through practice with the invention; the same being realized through the instrumentalities and combinations pointed out in the appended claims.

20 The invention consists in the novel parts, constructions, arrangements, combinations and improvements herein shown and described.

The accompanying drawings, referred to 25 herein and constituting a part hereof, illustrate one embodiment of the invention, and together with the description serve to explain the principles thereof.

Of the drawings:—

30 Figure 1 is a side elevation of a machine constructed in accordance with the principles of the invention;

Fig. 2 is an end view, looking at Fig. 1 from the left;

35 Fig. 3 is a top plan corresponding to Fig. 1; and

Fig. 4 is a fragmentary detail of a quick return device for the label carrier.

Referring by way of example to the embodiment illustrated in the accompanying drawings, a base 1 is provided, which serves 40 as a support and guide for the traveling carriage, as well as supporting other parts of the mechanism. The upper portion of the

45 base 1, at the top of the side walls 2 and 3, is formed into guideways 4 and 5, which extend longitudinally along the top of the base 1. The label carriage 6 has its under part provided with longitudinally disposed

50 guiding recesses formed to fit the guideways 4 and 5. The guideways are shown undercut on their exterior sides, and the base of the carriage 6 overhangs the guideways at either side, as best appears from

Figs. 2 and 3. Thus a very strong, simple 55 and economical construction is provided, the guideways being self cleaning and also well protected from dust, grit and other kinds of dirt.

In the embodied form of carriage, a label 60 clamping plate 7 is preferably integral with, or attached in fixed position to, the carriage base 6. The clamping plate 7 is shown cast integral with the base 6, and with reinforcing webs or struts 8 between the clamping plate and the base. The other label clamping plate 9 is likewise supported on the base 6 and is movable on such base to and from the plate 7, to accommodate gangs of labels α of varying numbers and thicknesses. As 70 embodied, the clamping plate 9 has a horizontally extending base 10 resting upon the top of the carriage base 6, and being slideable to and fro therealong.

Means are provided for holding the 75 clamping plate 9 in fixed position upon the base 6 to firmly clamp the labels during the marking or notching thereof. As embodied, there is provided in the carriage base 6 a T shaped slot 14, with the wider part thereof 80 at the bottom. In said slot is a bolt 15, with its head in the wide part of the slot and the body of the bolt extending upwardly through the slot and also through an aperture in the base 10. The upper end of the 85 bolt 15 is screw-threaded to take a wing nut 16. By loosening the nut the clamping plate 9 may be moved backwardly to receive the gang of labels α , and then may be moved forwardly to clamp the labels in position, 90 the nut 16 being screwed down to hold the plate 9 in position.

Suitable label notching means are provided, and in the embodied form thereof the label notching means comprises a rotating 95 saw 17, preferably located at the side of the machine. Means for rotating the saw are provided and in one aspect of the invention, connections are provided between the label carriage and saw whereby they may 100 be driven together, and in accordance with one feature of the invention, the power is supplied by hand or otherwise by the operative. As embodied, the saw 17 is mounted upon and fixed to rotate with a shaft 18, 105 which shaft is preferably vertically disposed at the side of the machine. Shaft 18 is journaled in a bearing 19 formed in, or

connected to, the machine base 1 by a web or bracket 20, extending outwardly from the base 1. Fixed on the shaft 18 is a bevel gear 21 located at the top of the journal 19, 5 and having its hub 22 secured to the shaft 18 to rotate therewith. Meshing with the gear 21 is a bevel gear 23, fixed to a shaft 24. Shaft 24 extends longitudinally along the base 1, and is journaled in supports 25 10 and 26, carried upon the base 1 by means of brackets 27 and 28. Fixed to the shaft 24 is a crank 29 to rotate the shaft.

In accordance with that aspect of the invention whereby the label carriage and label 15 notching means are driven together, and as embodied and illustrated, the shaft 24 is screw-threaded, and is embraced by a nut 34, which nut is carried on an arm 35, fixed to the base 6 of the label carriage.

20 Thus, as the shaft 24 is rotated, the label carriage is traveled slowly along, and the saw 17 is rotated to notch the edge of the labels *x* as they pass. In practice, it will be generally found advantageous to give the 25 saw a much higher speed than is indicated in the drawings, which may readily be done by changing the size of the screw-thread on the shaft and the ratio of the gearing.

Means are provided by the invention for 30 changing the relative position of the labels and the notching means, to bring the notches at the desired places in the labels, and for this purpose the saw 17 is preferably positionable along the shaft 18. As embodied, 35 the shaft 18 is screw-threaded, and threaded thereon are two internally screw-threaded clamping plates or mandrels 37 and 38, between which the saw 17 is firmly clamped in the desired position. Marks or indications 40 could be placed upon the shaft to indicate the various selected positions. Thus, the saw may be moved up and down on the shaft so as to notch the gang of labels in any desired position, to correspond to the date 45 indications wanted.

Means are provided by the invention for 50 positioning the labels relatively to the saw, and to regulate the depth of cut of the saw. As embodied, a movable gage plate 40 is provided, having attached thereto a plurality of bolts 41, which bolts are screw-threaded into apertures in a plate 42, fixed upon the carriage base 6. The labels are positioned so as to receive the notching cut, while the saw 55 clears the clamping plates 7 and 9.

In Fig. 4 of the drawings is shown an embodiment of a quick return for the label carriage if this is desired. For this purpose, the arm 35 is shown pivotally jointed 60 at 44, and the nut 34 is shown as a half nut, the shaft 24 in such case having a square thread. A spring 45 is arranged to throw either side of the pivotal center 44, and a finger piece 46 is provided on the half nut 65 34. The half nut 34 may thus be moved into

engagement with the shaft 24 for the forward feed and may be moved clear of the shaft 24 for the free return of the label carriage. In either case, the spring 45 will hold the half nut 34 either in engagement 70 with the shaft 24 or clear thereof as desired.

The machine is of simple, strong and economical construction, and does not require a motor or electric or other power for its 75 operation, a single operative supplying and removing the labels and also running the machine.

It will be understood that changes may be made from the particular constructions 80 shown and described, within the scope of the accompanying claims, without departing from the principles of the invention, and without sacrificing its chief advantages.

What I claim as my invention and desire 85 to secure by Letters Patent is:—

1. A label dating machine including in combination a base having carriage guideways, a carriage slideable therealong, label clamping plates adjustable on said carriage, 90 a saw mounted on the base at one side of the carriage, a rotatable shaft mounted in the base, and connections therefrom for rotating the saw and sliding the carriage along its guideways past the saw to notch the edges 95 of the gang of labels.

2. A label dating machine including in combination a base having carriage guideways, a carriage slideable therealong, label clamping plates adjustable on said carriage, 100 a saw mounted on the base at one side of the carriage, a rotatable screw shaft mounted in the base, gear connections between the shaft and the saw, a threaded member connected with the carriage and engaging the screw shaft to slide the carriage past the saw to notch the edges of the gang of labels.

3. A label dating machine including in combination a base having carriage guideways, a carriage slideable therealong, label 110 clamping plates adjustable on said carriage, a saw mounted on the base at one side of the carriage, a rotatable screw shaft mounted in the base, gear connections between the shaft and the saw, a threaded member connected with the carriage and engaging the screw shaft to slide the carriage past the saw to notch the edges of the gang of labels, said threaded member being detachable from the threaded rod for a quick return of the carriage.

4. A label dating machine including in combination a base having carriage guideways, a carriage slideable therealong, label clamping plates adjustable on said carriage, 125 a saw mounted on the base at one side of the carriage, a rotatable shaft mounted in the base, and connections therefrom for rotating the saw and sliding the carriage along its guideways past the saw to notch the edges of 130

the gang of labels, and means for varying the relative positioning of the saw and the gang of labels to indicate different dates in the edges of the labels.

5 5. A label dating machine including in combination a base having carriage guideways, a carriage slideable therealong, label clamping plates adjustable on said carriage, a saw mounted on the base at one side of the carriage, a rotatable shaft with a square thread, a threaded member carried by the carriage and movable into and out of engagement with the threaded shaft, and means for rotating the saw.

10 15. 6. A label dating machine including in combination a base having carriage guideways, a carriage slideable therealong, label clamping plates adjustable on said carriage, a saw mounted on the base at one side of the carriage, a rotatable shaft with a square thread, a threaded member carried by the carriage and movable into and out of engagement with the threaded shaft, means for holding the threaded member in or out of 20 25 engaging position and means for rotating the saw.

7. A label dating machine including in combination a base having carriage guideways, a carriage slideable therealong, label clamping plates adjustable on said carriage, a saw mounted on the base at one side of the carriage, a rotatable screw shaft mounted in the base, gear connections between the shaft and the saw, a threaded member connected 30 35 with the carriage and engaging the screw shaft to slide the carriage past the saw to notch the edges of the gang of labels, said threaded member being detachable from the threaded rod for a quick return of the carriage, and means for holding the threaded

member in engaging or detached position with respect to the screw rod.

8. A label dating machine including in combination a base having carriage guideways, a carriage slideable therealong, label clamping plates adjustable on said carriage, a saw mounted on the base at one side of the carriage, a rotatable shaft mounted in the base, and connections therefrom for rotating the saw and sliding the carriage along its guideways past the saw to notch the edges of the gang of labels, a shaft for the saw, and means for adjusting the saw along its shaft to position the dating notches in the edges of the labels. 45 50 55

9. A label dating machine including in combination a base having carriage guideways, a carriage slideable therealong, label clamping plates adjustable on said carriage, a vertical saw shaft mounted on the frame at one side of the carriage path, a saw thereon, means for positioning the saw along its shaft to indicate different dates and means for sliding the carriage past the saw. 60

10. A label dating machine including in combination a base having carriage guideways, a carriage slideable therealong, label clamping plates adjustable on said carriage, a vertical saw shaft mounted on the frame at one side of the carriage path, a saw thereon, a horizontal screw shaft extending along the base and a screw threaded member carried by the carriage and engaging the screw shaft. 65 70

In testimony whereof I have signed my name to this specification in the presence of two subscribing witnesses. 75
